UNITED STATES PATENT OFFICE.

GEORGE CONSTANTINESCO, OF WEYBRIDGE, ENGLAND.

CARBURETOR.

Application filed February 7, 1922. Serial No. 534,749.

To all whom it may concern:

Be it known that I, GEORGE CONSTANTINESCO, a subject of the King of Great Britain and Ireland, residing at "Carmen Sylva," 5 Beechwood Avenue, Oatlands Park, Weybridge, in the county of Surrey, England, have invented certain new and useful Improvements in Carburetors, of which the following is a specification.

10 The invention consists in improvements relating to carburetors having an inverted or down flow fuel supply nozzle, and it consists in disposing the outlet in relation to the throttle and in shielding the outlet so that while the incoming fluid is introduced into the main body of the air current, it is at the same time shielded from the direct action of the current and subject only to the suction in the air passage.

15 20 In the accompanying drawings, Figure 1 is a cross section, and Figure 2 a longitudinal section through a carburetor. Fig. 3 is an elevation of the conical hood showing the fuel outlet.

25 The drawings show by way of example a suitable down flow carburetor, but no claim is made for its special features, as the invention is applicable to any carburetor of this type.

30 *a* is the float chamber and *b* the mixing chamber. Screwed into the bottom of the float chamber is a partition *c* projecting above the level of the fuel in the float chamber when the engine is not running. Projecting downwards from the center of the cover *d* of the float chamber is a partition *e*. The nozzle *g* is screwed into the lower end of a central rod *h* which is screwed into the partition *c*, the passages *i* for petrol to pass to the nozzle being formed in the lower end of the rod *h*. The float consists of a cork attached to the free end of a hinged member *l* of the form illustrated. The vertical portion of the arm *l* near the hinge *m* is arranged to bear against the needle valve *n* controlling the flow of petrol into the float chamber. At one side of the float chamber there is provided a passage *o* leading through a restriction *p* from the induction pipe *b* to the interior of the sleeve *e*. A disk valve

q controls a passage leading from the main space within the float chamber into the passage *o* to limit the suction effect which can be obtained inside the sleeve *e*. A slotted plug *t* is provided to control the flow of air into the float chamber.

According to my invention the axis of the throttle is placed immediately below the nozzle *g*, and surrounding the nozzle is an inverted conical hood or baffle *u*. The baffle extends downwardly as nearly as possible to the throttle axis, and is pointed so as not to interfere with the throttle. It has perforations *v* on the side towards the air inlet and a slot *w* on the other side. The access of the air on the inlet side to the interior of the nozzle is therefore somewhat restricted, and this restriction on the inlet side and freedom of outlet on the other side prevent the vertical component of the air current from interfering with the flow through the nozzle when the throttle is nearly closed. The reasons for locating the throttle axis immediately under the nozzle are two. In the first place the fuel can be introduced into the middle of the air current at or near the place where the throttling is greatest and where therefore changes in velocity and therefore in suction have their greatest effect. Secondly it enables the throttle to be used for restricting the air supply before it reaches the fuel, thus facilitating starting in cold weather and avoiding the necessity of resorting to other means for restricting the air inlet, such, for instance, as the common practice of the introduction of a rag.

What I claim is:

In a down flow carburetor, a mixing chamber into which the fuel is discharged through an orifice, a throttle turning about a horizontal axis arranged vertically below said orifice, and a conical hood covering said orifice and extending into the mixing chamber to a point close to the axis of the throttle, said hood having an air inlet and a mixture outlet with the outlet of greater capacity than the inlet.

In testimony whereof I affix my signature.
GEORGE CONSTANTINESCO.
